Inventor

T. L. Sopher

By *Clarence A. O'Brien*

Attorney

UNITED STATES PATENT OFFICE.

TED LEONE SOPHER, OF ABILENE, KANSAS, ASSIGNOR OF ONE-HALF TO WILLIAM JOHNSON AND ALBERT JOHNSON, BOTH OF ABILENE, KANSAS.

DISPLAY CASE.

Application filed March 19, 1926. Serial No. 95,981.

My present invention pertains to display cases of the tiltable type.

One of the objects of my invention is the provision of a display case having means, 5 whereby the same is adequately ventilated.

Another object of the invention is the provision of a display case having a body and a cover so relatively arranged that shifting of the position of the body relative to the 10 cover will be attended by opening of the body so that access may be readily gained to the interior thereof.

Another object is the provision of a construction in which the body is so mounted 15 that it may be moved to and from closed position with great facility and with little effort.

To the attainment of the foregoing, the invention consists in the improvement as 20 hereinafter described and definitely claimed.

In the accompanying drawings, forming part of this specification:—

Figure 1 is a side elevation of the preferred embodiment of my invention, end 25 portions of one side wall of the body being broken away to illustrate the ventilating diaphragms.

Figure 2 is a top plan view of the case.

Similar numerals of reference designate 30 corresponding parts in both views of the drawings.

It is within the purview of my invention to construct the main frame in any manner compatible with the purpose of the invention. I prefer, however, to have the said main frame comprise two pairs of uprights 1 and bars 2 fixed to the upper ends of the uprights 1 and extending therefrom as designated by 3 so as to constitute overhanging 35 supports. Interposed between and carried by uprights 1 at opposite sides of the main frame are transverse rods 4, the foremost rod 4 being arranged in a horizontal plane below that of the other rod or bar 4.

Hingedly connected at 5 to the overhanging portions 3 of the main frame is a vertically swingable cover or closure member 6, the said cover or closure member 6 being preferably, though not necessarily, formed 45 by an open frame 7 and a pane 8 of glass or other appropriate transparent material disposed in said frame 7. By comparison of Figures 1 and 2, it will be noted that in the preferred construction the cover 6 is provided with apertured ears 9, and that the

said ears 9 are loosely mounted on a transverse rod 10 interposed between and carried by the overhanging portions 3 of the main frame near the outer ends of said overhanging portions.

The body of my novel case is designated generally by 11, and within the purview of my invention, may be made of any material or materials compatible with its purpose. As illustrated the said body 11 comprises a 65 bottom wall and side walls and also comprises end walls 12 and 13 of glass or other appropriate transparent material, and ventilating diaphragms 14 and 15 of reticulated or other appropriate material, the said diaphragms being designed to permit of an adequate circulation of air through the casing body for the sake of ventilation. As shown in Figure 1, I prefer to interpose the screen 14 between the upper edge of the transparent wall 12 and the upper edges of the side walls of the body 11, and also prefer to interpose the screen 15 between the lower edge of the transparent wall 13 and the bottom of the body 11. At its rear end the 70 body 11 is equipped with an appropriately connected handle or hand grasp 16.

In accordance with the chief part of my invention, the casing body 11 is provided in its bottom or at its underside with three 80 notches 17, 18 and 19.

Normally the casing body 11 rests as shown by full lines in Figure 1, the notch 17 receiving the transverse rod 4, the notch 19 receiving the rear transverse rod 4 and the 90 cover 6 resting in inclined position on the body 11 so as to close the same, and this in such manner that the contents of the body 11 are efficiently displayed.

From the foregoing it will be understood 95 that when a person in authority desires to gain access to the interior of the body 11, it is simply necessary for such person to apply a little stress to the body 11 and draw the same rearwardly so as to separate the notch 100 19 from the rear rod 4 and the notch 17 from the front rod 4 and place the notch 18 over the rod 19, whereupon the body 11 may be tilted to the dotted line position in Figure 1, with the result that the cover 6 will be 105 raised by the upper forward corner of the body 11, and a large portion of the upper side of the body 11 will be uncovered so that access may be had with facility to all 110 portions of the interior of the body 11.

Manifestly by reversing the operation described, the body 11 will be restored to the full line position in Figure 1, and the cover 6 will gravitationally assume a position upon and close the upper side of the body 11.

Notwithstanding the display capacity of my novel case, and the facility with which the body 11 may be manipulated, it will be noted that the case as a whole is simple and inexpensive in construction, is susceptible of being so made as to constitute an ornamental piece of store furniture, and in general is well adapted to withstand the usage to which devices of corresponding character are ordinarily subjected.

While I prefer the construction herein specifically described, I do not desire to be understood as limiting myself to the said specific construction, my invention being defined by my appended claims within the scope of which modifications may be made without departure from my invention.

Having thus described my invention, what I claim and desire to secure by Letters Patent, is:—

1. In combination, a frame having spaced side portions and overhanging portions extending from said side portions and also having transverse rods interposed between 30 and carried by the side portions, the said transverse rods spaced apart and the forward rod being arranged in a horizontal plane below that of the rear rod, and further having a transverse rod interposed between 35 and carried by the ends of the overhanging portions, a cover having at one end upstanding apertured lugs loosely receiving the last-named transverse rods, said cover being free to swing vertically, and a body 40 arranged between said side portions and having its top open and arranged to be opposed to said cover, and further having in its bottom portion three spaced notches for cooperation with the transverse 45 rods between the side portions; the rear transverse rod being in a vertical plane spaced in front of the vertical plane of the center of movement of the cover.

2. In combination, a frame having spaced 50 side portions and overhanging portions extending from said side portions and also having transverse rods interposed between and carried by the side portions, the said transverse rods spaced apart and the forward rod being arranged in a horizontal 55 plane below that of the rear rod, and further having a transverse rod interposed between and carried by the ends of the over-

hanging portions, a cover having at one end upstanding apertured lugs loosely receiving 60 the last-named transverse rod, said cover being free to swing vertically, and a body arranged between said side portions and having its top open and arranged to be opposed to said cover, and further having in 65 its bottom portion three spaced notches for cooperation with the transverse rods between the side portions; the said cover having a pane of transparent material, and said body having end walls formed partly of transparent 70 material and partly of screen material, one of the said screen portions being arranged adjacent to the bottom of the body and the other screen portion arranged adjacent to the top of the body, and the said rear transverse rod being arranged in a vertical plane in front of the vertical plane of the center of movement of the cover.

3. In combination, a frame having spaced side portions and also having spaced transverse rods between said side portions with one of said rods arranged in a plane below that of the other, a vertically swingable cover pivotally connected at one end between the side portions at a point above and in rear of the higher of the first-named transverse rods, and an endwise shiftable and swingable body, open at its upper side and adapted to have said side normally opposed to and closed by the cover and having at 90 its bottom three spaced notches for cooperation with the first-named transverse rods, and said rod in a vertical plane in front of the vertical plane of the center of movement of the cover.

4. In combination, a frame, a vertically swingable cover carried by the frame, and an endwise shiftable and swingable body supported by the frame and having an open upper side opposed to and adapted to be 100 normally closed by the cover; said body having the center of its swinging movement in a vertical plane spaced from the vertical plane of the center of movement of the cover, and said body relatively arranged 105 when shifted endwise and canted or tilted to raise the cover from the major portion of the upper side of the body; the said frame including spaced transverse rods one in a plane below that of the other, and the said body having in its bottom portion three spaced notches for cooperation with said rods.

In testimony whereof I affix my signature.

TED LEONE SOPHER.
